UNITED STATES PATENT OFFICE.

CHARLES A. NELSON, OF UTICA, NEW YORK, ASSIGNOR TO SAVAGE ARMS CORPORATION, OF UTICA, NEW YORK, A CORPORATION OF DELAWARE.

EXTRACTOR MECHANISM FOR FIREARMS.

Application filed January 30, 1920. Serial No. 355,092.

To all whom it may concern:

Be it known that I, CHARLES A. NELSON, a citizen of the United States of America, and residing in the city of Utica, county of Oneida, and State of New York, have invented the following described Improvement in Extractor Mechanism for Firearms.

My invention relates to the extractor ring of rotary bolts. The extractor ring is an annular band rotatably mounted in a circumferential groove in the bolt forming the support for the extractor which is a longitudinal spring member having a hook at its forward end to engage with and draw the exploded cartridge. Heretofore the extractor ring has commonly been made of one piece machined and bent to shape around the bolt and secured by its meeting ends to the extractor. Since the ring must fit the groove snugly and must also be easily rotated there-in, the manufacture and assembly of these single piece bands, as also their repair when broken, are fairly difficult operations.

According to this invention the manufacture and assembly of such rings is simplified and their cost reduced. The new ring is made up of a plurality of parts each of which is properly curved before assembly on the bolt, and so formed that it can be quickly assembled with the other parts to form a suitable support for the extractor. These ring parts may be two in number and each may be a duplicate of the other so that the rings can be cheaply made; they may be produced in pressing or stamping machines.

In the accompanying single sheet of drawing, Fig. 1 is an elevation of a breech-bolt with the extractor in section and a two-part ring, a preferred form, disassembled and in perspective; the extractor is in position ready for assembly with the ring. Fig. 2 is an elevation of the forward part of the devices of Fig. 1 showing the ring parts assembled on the bolt and the extractor engaged therewith. Fig. 3 is a plan view of Fig. 2 and Fig. 4 is a section on line 4—4 of Fig. 2.

The breech-bolt 10 will be understood to be shown in conventional form, having the usual operating side lever 11, locking lugs 12, extractor ring groove 15 and other necessary parts, whereby it constitutes a suitable closure to the breech of the fire arm. The extractor 14 will also be recognized as of common form, being provided with the usual

cartridge hook 21 and a lug 20 by which it engages the groove 13 in the bolt, to be thereby normally held against longitudinal displacement thereon. Near its middle the extractor is thickened and formed with a longitudinal T-slot 17 by which it engages and draws together the ends of the extractor ring. This slot is open at its rear end so that it may be pushed rearwardly over the ends of the ring to the position of Fig. 2 in which it is retained by the engagement of the lug 20 in groove 13. Between its middle and ends the extractor bar is thin in order to be elastic. In the assembled position it will be understood that the lug 20 rides in the groove 13 as the bolt rotates while the hook 21 extends radially over the forward edge of the bolt 10 and is adapted to snap over the rim of the cartridge when the bolt is locked up.

The extractor ring comprises a plurality of complementary parts; preferably the parts are similar so far as may be, and preferably they comprise two semi-annular parts like 25 and 26 of identical size and shape. Each of the ring parts, of whatever shape and number, is made with an interior curvature of substantially the same radius as the bottom of the groove 15 and of a corresponding width and thickness. They are inserted in the groove 15 and there fastened together in any suitable way to form the whole ring, and are preferably fastened by an interlocking joint (Fig. 3) constituted of a notch 27 formed in the edge of each part to receive the hook 28 of the other. The opposite ends of the ring are formed straight at 29, and then turned outwardly forming the oppositely directed heads 30 which are received in the T-slot 17 when the extractor bar is pushed rearwardly to position of Fig. 2 as above described. As thus formed the assembled ring appears and functions exactly the same as prior one-piece rings, but has the advantages above mentioned. It will be apparent that the principle of the invention can be applied in different ways to different types of bolts and extractors, there being no limitation to the particular mechanism above taken for illustration.

Claims:

1. An extractor ring to fix a separate extractor to the bolt, said ring comprising a plurality of parts adapted to be fitted to-

105

- gether to form a complete ring and provided with means to detachably support the extractor thereon.
2. The combination of an extractor and a separate extractor ring comprising a plurality of ring parts, each permanently curved before assembly on the bolt to substantially the radius of the completed ring and all said parts being fastened together and adapted to support the extractor.
3. An extractor ring comprising two similar ring parts, each provided at one end with means interlocking with the other part and provided at the other end with means for engaging the extractor.
4. An extractor ring comprising two similar semi-annular parts, each provided at one end with an interlocking notch formed in one edge, whereby the two parts can be interlocked to form the complete ring, the other ends of the two parts being connected to the extractor.
5. An extractor ring comprising two similar semi-annular ring - parts permanently shaped to fit the bolt before assembly therewith and united by a joint at their adjacent ends, the opposite ends of the two parts being united by the extractor.
6. The combination of a circular bolt, an elastic bar-like extractor laid along the bolt, the bolt being provided with a circumferential extractor ring groove disposed near the middle of the extractor and an extractor ring comprising two semi-annular parts, laid in said groove, each of said parts being provided with a notch in one end to interlock in the notch in the other and the opposite ends of the ring parts being provided with means for attachment to the extractor, whereby the extractor is held on the bolt.
- In testimony whereof, I have signed this specification.

CHARLES A. NEILSON.
